SMOKING PIPE

Paul A. Peterson, Mellette, S. Dak.

Application May 7, 1946, Serial No. 667,746

1 Claim. (Cl. 131—203)

1

My present invention relates to an improved smoking pipe and more particularly to the construction of a smoking pipe wherein the saliva from the mouth of the smoker is prevented from passing through the bit and stem into the bowl.

The saliva from the mouth of the smoker has always been objectional in that it will flow down the stem of the pipe into the bowl, or will mix with the tobacco juices in pipe tobacco and will return to be sucked into the mouth of the smoker causing a most unpleasant sensation. In cold climates it has been found that the saliva flowing into the stem has frozen and prevented the proper functioning of the pipe until the frozen moisture is thawed, or the moisture removed by continually shaking the pipe to remove the saliva.

In the accompanying drawings I have disclosed one complete example of the physical embodiment of my invention according to the best mode I have thus far devised but it will be understood that various changes and alterations may be made in the exemplified structure within the scope of the appended claim.

In the drawings:

Figure 1 is a side elevational view of the pipe of my invention.

Figure 2 is a top plan view thereof.

Figure 3 is a vertical longitudinal sectional view.

Figure 4 is a transverse vertical sectional view taken at line 4—4 of Figure 3.

Figure 5 is an enlarged fragmentary sectional view showing certain constructional details of the pipe;

Figure 6 is an enlarged fragmentary sectional view showing the portion of the pipe which is inserted in the smoker's mouth.

Referring now to the drawings wherein like characters indicate like parts I have illustrated a smoking pipe having a body 2 and a bowl 4. The bowl 4 is integral with the body and is formed with thickened walls 5. An ash receptacle 6 is shown forward of the bowl and this receptacle is open ended as at 8.

A screen 10 is located in an annular groove 11 in the base of the bowl to prevent the passage therethrough of ashes and bits of tobacco, and the stem 12 of the pipe being connected with the base of the bowl is fashioned with a bit 14. A ring 26 serves to maintain the screen in its proper place in the bowl.

In order to prevent the flow of saliva from the bit through the stem, I provide an open-ended tube of copper or aluminum, or other suitable material as 16 through the thickened wall 5 of the bowl into and through the hollow stem and through the bit 14.

This tube terminates at 18 exteriorly of the wall 5 of the bowl 4 and above the ash receptacle 6. This tube 16 is the only passage through the bit, and the smoke from the burning tobacco is drawn by suction through the screen into the stem and thence through a port or aperture 22 into the tube and thus through the bit.

2

Vents 20 in the tube 16 communicate with vents 25 in the wall 5 of the bowl to permit the escape of heated moisture in the tube and the moisture is substantially vaporized due to the location of the tube at the hottest part of the pipe, i. e., in the wall of the bowl.

I also employ within the tube 16 a tufted wire similar to the conventional pipe cleaner and illustrated as at 24 to absorb and collect moisture and juices therein.

The tube being of copper or aluminum will be an efficient means of transferring heat from the smoke in the stem to the exterior of the pipe and will result in a cleaner cooler smoke without the unpleasant saliva flow into the bowl. The normal passage of smoke is through the screen 10, into chamber 29, thence through aperture 22, and into tube 16, whereby the smoke can be drawn into the smoker's mouth. Any saliva that collects in the bend of the tube 16 can be brought into contact with the member 24 by tilting the pipe, the member 24 absorbing or retaining this fluid, and the saliva in the tube 16 will be vaporized by heat from the hot smoke, as well as by heat transfer from the burning tobacco. In other words, the burning tobacco will heat the adjacent portion of the pipe bowl so that the vaporized saliva passes out through the vents 20 and 25. The aperture 22 is of sufficient diameter that saliva will not block this aperture.

Having thus fully described my invention what I claim as new and desire to secure by Letters Patent is:

In a smoking pipe, the combination with a bowl, an open-ended receptacle for containing ashes arranged forwardly of said bowl, a stem arranged rearwardly of said bowl, and a bit extending from an end of said stem adapted to be inserted in the smoker's mouth, of a means for preventing the flow of saliva from the smoker's mouth from contacting with the interior of the stem, said means comprising an open-ended tube arranged longitudinally in said pipe, an end of said tube extending through said bit, and the other end of said tube terminating above said receptacle, an intermediate portion of said tube passing through a wall of said bowl and supported by said wall, there being an aperture arranged in said tube for the ingress therethrough of smoke, and means for absorbing fluid in said tube.

PAUL A. PETERSON.
